CLOTHES HANGER FOR AUTOMOBILES

Kenneth A. Richey, Long Beach, Calif.

Application April 14, 1949, Serial No. 87,525

2 Claims. (Cl. 224—29)

1

This invention relates to a clothes hanger or support for automobiles in which clothes can be supported back of the front seat of the vehicle in a simple, effective and convenient manner.

An object of my invention is to provide a clothes support for automobiles in which said support extends longitudinally from the front seat to the sill at the back window of the vehicle.

Another object of my invention is to provide a novel clothes supporter of the character stated in which the supporter extends longitudinally of the vehicle and thus does not interfere with the rear vision of the driver.

Another object of my invention is to provide a novel clothes supporter of the character stated, which is simple in construction, inexpensive to manufacture, and which can be easily applied to the vehicle.

Other objects, advantages and features of invention may appear from the accompanying drawing, the subjoined detailed description and the appended claims.

In the drawing:

Figure 1 is a diagrammatical longitudinal sectional view of a vehicle showing my clothes supporter in operative position.

Figure 2 is a fragmentary side elevation of the supporting rod.

Figure 3 is a perspective view of a sleeve, which is attached to the rod.

Figure 4 is a fragmentary side elevation of a portion of the supporting rod with parts broken away to show interior construction.

Figure 5 is a perspective view of one of the support fittings.

Figure 6 is a perspective view of another support fitting.

Referring more particularly to the drawing, the usual vehicle in which my garment support can be mounted consists of a front seat 1 and a sill 2 at the rear of the vehicle and immediately back of the rear seat 3. The sill or ledge 2 is immediately in front of the rear window of the vehicle and is usual and well known in the art.

A fitting 4 includes a plate 5, which is bolted or otherwise secured to the rear of the front seat 1, and a sleeve 6 is fixedly attached to or may be an integral part of the plate 5. The second fitting 7 also consists of a plate 8 and a sleeve 9 affixed to the plate or an integral part thereof. A second fitting 7 is secured to the sill 2 at the rear of the vehicle, substantially as shown in Figure 1.

The supporting rod 10 is preferably formed of tubular stock, although this is not essential. The support 10 includes a vertical section 11, which fits into the socket 6. The support 10 also includes a rear section 12 which fits into the socket 9, substantially as shown.

A center section 13 is formed with a socket 14 at the forward end, which fits over the top of the

2

front section 11, and a socket 15 at the rear, which fits over the end of the section 12. These slip joints 14 and 15 permit the entire hanger to be disassembled into relatively short sections so that it can be easily stored. The slip joints 14 and 15 are a relatively close fit so that the entire assembly will be quite rigid.

A pair of sleeves 16 and 17 are secured to the center section 10 of the hanger, and each sleeve 10 includes a finger 18, fixedly secured thereto. A coil spring 19 rests on the tubular portion 10 of the hanger and fits between the sleeve 16 and 17 and under the finger 18, thus holding the spring against endwise movement on the tubular section 10. The garments to be carried are hung on the usual hangers and these hangers, when placed between the coils of the spring 19, will hold the clothes against sliding longitudinally along the rod forming the clothes support.

Having described my invention, I claim:

1. A clothes support for automobiles including a socket, means securing said socket to the front seat of the automobile, a second socket, means securing the second socket at the rear of the automobile, and a supporting rod fitting in both of said sockets and extending longitudinally of the automobile and adjacent the roof, a spring mounted on said rod and means on the rod engageable by the spring to limit endwise movement of the spring.

2. A clothes supporter for automobiles comprising a front fitting having a socket therein, means securing the front fitting to the front seat of an automobile, a second fitting, said second fitting having a socket therein, means securing the second fitting to the rear of the automobile, a supporting rod fitting into both of said sockets said rod extending longitudinally of the automobile and adjacent the roof, a plurality of segments forming said supporting rod, slip joints connecting the segments, whereby the supporting rod may be disassembled, a spring mounted on the supporting rod and means on the supporting rod engageable by the spring to limit endwise movement thereof.

KENNETH A. RICHEY.
